APPARATUS FOR TREATING TEXTILE FABRICS

Charles George Hatay, Georgetown, Mass., assignor to E-Z Mills, Inc., New York, N. Y., a corporation of New York

Application April 28, 1950, Serial No. 158,825

10 Claims. (Cl. 26—18.5)

1

This invention relates to the treatment of textile fabrics, and particularly to an apparatus for relieving internal stresses in fabrics incident to shrink-proofing them.

In my copending application Serial No. 136,958 filed January 5, 1950, I have disclosed a shrink-proofing process, applicable especially to knitted fabrics, which comprises essentially the following steps: (1) The fabric, while completely wetted, is placed in a substantially tensionless and compressionless condition to cause displacement of the fabric fibres by the internal stresses therein, so that these stresses are relieved or eliminated with the rearrangement of the fibres. In this first or de-stressing operation, the fabric is preferably spread under the surface of a water bath so that the weight of the fabric is compensated by its buoyancy, and the friction of the water is applied to the fabric on a surface which is many times greater than the acting surfaces of the rollers of a conventional spreader. (2) An alternating electric current is passed through the fabric, while thus de-stressed and retaining at least some of the wetting agent, to cause internal heating of the fabric di-electrically until it is substantially freed of the wetting agent by evaporation.

I have found that the combination of these two steps is highly effective for shrink-proofing fabrics, the shrinkage of a test length of knitted cotton fabric, treated by my process, being considerably less than 1% in a subsequent laundering.

For best results in shrink-proofing fabrics according to the above-described process, the mechanical handling of the fabric in the de-stressing operation should be carefully controlled to avoid heavy external stresses on the fabric. The application of heavy tension to the fabric during this period tends to reduce the shrink-proofing effect, evidently because it distorts the fibres from their relaxed positions or forms which they assume in the de-stressing operation and thereby creates inter-fibre, and intra-fibre stresses which remain in the fabric upon completion of the stabilizing or "setting" operation.

The present invention, therefore, has for its principal object the provision of an apparatus by which the fabric can be treated expeditiously in a continuous operation to relieve the internal stresses in the fabric, prior to the stabilizing or "setting" operation.

The new apparatus comprises a container for a liquid wetting agent through which the fab-

2

ric is transported lengthwise in a submerged path by a conveyor which operates to move the fabric under substantially tensionless and compressionless conditions. The apparatus also comprises a spreader located in the container below the surface of the liquid and operable on the submerged fabric to spread it under the liquid surface while leaving the fabric in its relaxed condition. The spreader in its preferred form is stationary and includes an air pipe or other means in the container for introducing air into the liquid below the path of the submerged fabric, and a guide plate immersed in the liquid above the fabric and having a bottom surface which directs the air bubbles laterally of the fabric path so as to spread the fabric against the plate bottom. In thus spreading the fabric while submerged and moving in a relaxed condition through the liquid, the apparatus differs from conventional fabric spreaders wherein the fabric is stressed by rollers or tensioning devices, for example, incident to the spreading operation. The present apparatus not only spreads the fabric without imposing appreciable stresses in it, but also moves the fabric through the liquid in a near stress-free condition because of the fabric being supported by its own buoyancy in the liquid. To increase the de-stressing effect of the apparatus, it may also be provided with an oscillating device submerged in the liquid and engageable with the fabric passing through the container to impart a gentle shaking movement to the fabric.

In the preferred form of the apparatus, the liquid container is in the form of a trough communicating at one end with a receptacle in which the fabric to be de-stressed is placed in a more or less random state. As the fabric moves lengthwise from the receptacle to the trough, the conveyor passes it over an oscillating air duct which introduces air into the liquid below the fabric. The oscillating device serves to untangle the fabric during its passage to the trough and also to inflate the fabric so that it floats to the surface of the liquid. Minute bubbles of the air tend to adhere to the fibres and thereby provide added buoyancy to the fabric as it moves along its submerged path in the trough. At the discharge end of the trough, the fabric engages an endless belt which is partly submerged in the liquid and operates as part of the conveyor to withdraw the de-stressed fabric from the trough while maintaining it in

a substantially tensionless and compressionless condition.

For a better understanding of the invention, reference may be had to the accompanying drawing, in which

Fig. 1 is a longitudinal sectional view of a preferred form of the apparatus;

Fig. 2 is a plan view of the apparatus illustrated in Fig. 1 and

Fig. 3 is a sectional view on the line 3—3 in Fig. 1, showing details of the spreader.

Referring to the drawing, the de-stressing apparatus as there shown comprises a container 10 in the form of a trough which at one end opens into the upper part of a receptacle or tank 11. The opposite end of the trough is closed, as shown at 10a. The tank 11 and the trough 10 are filled with a liquid wetting agent, such as water, to the level A (Fig. 1), the tank 11 being provided with a level outlet 12. The fabric F, which as illustrated is in the form of an elongated sleeve or tube of knitted cotton fabric, is placed in a random-twisted condition in the tank 11 where it is in a completely wetted state and tends to float under the surface A of the water bath. One end of the fabric tube passes over a horizontal duct or pipe 13 having holes 13a spaced along the pipe between flanges or guides 13b. The pipe 13 is supported on an oscillating arm or pendulum 14 which is hollow and is connected to a source of compressed air (not shown), whereby air is blown continuously through the holes 13a in the upper surface of the pipe 13. In this way, the fabric tube is inflated, as shown at F', by the air from the oscillating pipe 13. The air is more or less confined between the pipe 13 and a pair of rollers 15 mounted in the opening between trough 10 and tank 11, although some of the air will continually escape through the mesh of the fabric as it passes to the rollers 15. Thus, the inflated part F' of the fabric tube will float on the surface A of the bath, and this floating action, in combination with the oscillations of the pipe 13, serves to untangle the fabric tube as it is drawn out of the tank 11. The oscillating pipe 13 not only serves as a fabric untangling device but also to give the fabric passing through the trough 10 an added buoyancy due to minute air bubbles adhering to the fabric fibres.

From the rollers 15, the fabric passes to a spreader which comprises a horizontal guide plate 16 extending across the trough 10 from one side to the other. The plate 16 is disposed below the surface A of the bath but above the path of the fabric F, and it is slightly bowed downward so that the lower face of the plate slants upward toward its side edges. The plate 16 is made of a water repellent, highly polished material, preferably a transparent plastic material, and is provided along its sides with air vents 16a. A compressed air pipe 17 has a horizontal section 17a extending longitudinally of the trough under the central portion of the curved plate 16, the horizontal pipe section 17a being provided with holes 17b spaced along the length of the pipe. The fabric F passes below the plate 16, so that air bubbles from the pipe 17a rise to the fabric at the central or lowermost portion of the plate and thus urges the fabric against the bottom surface of the plate. The plate 16 is imperforate except at its sides, and since the plate bottom slants from pipe 17a upwardly and outwardly toward the edges of the fabric path, the air bubbles from the pipe 17a are directed laterally

through and along the fabric under the plate, the bubbles finally escaping through the side openings 16a. In this way, the bubbles act to spread the fabric against the lower face of the plate 16, the highly polished surface of which serves to reduce the friction tending to oppose the spreading of the fabric by the bubble action.

The fabric from the spreader 16—17 passes under a roller 19, over a roller 20, and then under a roller 21, these rollers forming part of a conveyor for the fabric and extending transversely between the sides of the trough and below the surface A of the liquid. The intermediate roller 20 is driven by a belt 22 from a squirrel-cage electric motor 23. The belt 22 is arranged to provide a continuous slippage between the belt and the driving motor 23; but as the fabric is pulled along the trough 10, the transport roller 20 effects an additional pull on the fabric, the force of this pull being substantially constant due to the slippage between the belt 22 and the motor 23.

The fabric F passes from the transport rollers 19, 20, 21 to a second spreader comprising a plate 24 and an underlying perforated air pipe 25a, which are similar to the parts 16 and 17a, respectively, of the first air spreader.

From the second air spreader 24, 25a, the fabric passes between a pair of rollers 27 to a shaker or oscillating device comprising a pair of rollers 28 and 28a mounted on a carriage 29 suspended on one end of a flexible arm 30, the other end of the arm being mounted on a support 41. The arm 30 rests upon an eccentric 32 which is rotated by a suitable power source (not shown). As the fabric passes between the rollers 28 and 28a, it is subjected to a gentle shaking action below the surface of the bath by the vertical reciprocation imparted to the rollers through the eccentric 32. This oscillatory movement of the fabric, against the friction of the water, facilitates release of the internal stresses in the fabric fibres.

An endless belt 33, forming part of the fabric conveyor, is disposed in the trough 10 in front of the shaker device and receives the fabric after the shaking action. The belt 33 is mounted on a series of rollers 34, 34a, 34b, 34c and 34d. The fabric from the shaker device moves upon the endless belt 33 between the latter and an idler roll 35. The endless belt is driven from a suitable power source (not shown) by a drive belt 36 extending around a pulley 37 on one end of the roller 34.

At opposite sides of the tank 10 are vertical supports 39 having vertical slots 39a which receive removable studs 40a at the ends of a hollow perforated mandrel 40. The fabric from the endless belt 33 is wound around the mandrel 40 to form a coil 41. The mandrel 40 is not driven, but the coil 41 is caused to turn by friction on the endless belt 33, the coil being supported by the underlying rollers 34c and 34d over which the endless belt extends. As the diameter of the coil increases, due to winding of additional fabric on the coil, the studs 40a of the mandrel slide upwardly in the slots 39a of the supports 39. A squeeze roller 42, which is provided with a semi-rigid rubber surface, has studs 42a disposed in the slots 39a and rests upon the upper surface of the fabric coil 41. The squeeze roll 42 rides upwardly in the guide slots 39a as the mandrel 40 rises from the belt 33 and the underlying rollers 34c and 34d, due to enlargement of coil 41 as the winding proceeds. If desired, the weight of the roller 42 may be supplemented by weights

(not shown) mounted on the studs 42a, and the roller 42 may be provided with means (not shown) for automatically releasing the pressure of the roller on the coil 41 when the feed of the fabric along the trough is stopped.

In the operation of the de-stressing apparatus, the fabric tube is moved slowly along the trough 10 due to the pull imparted to the fabric by the roller 20 and the endless belt 33. Since the mandrel 40 is not positively driven, the apparatus avoids any heavy tension on the fabric as it is drawn through the liquid. The pulling of the fabric by the endless belt 33 acting on the bottom of the coil 41, and by the transport roll 20, may be supplemented by similar transport rolls located in other parts of the trough 10, so as to provide a uniform movement of the fabric along the trough under near tensionless conditions. By air-spreading the fabric between the curved plates 16-24 and the compressed air pipes 17a-25a, the fabric is supported in a flattened condition under the surface of the liquid by the buoyancy of the fabric in the liquid, whereby the fabric is placed under a substantially compressionless and tensionless condition while completely wetted. Because of the absence of heavy compression rollers or heavy tensioning of the fabric while it is moved through the liquid and then wound on the mandrel 40, the fabric fibres remain in the relaxed positions to which they were displaced by the treatment in the trough 10, whereby the fabric coil 41 is substantially de-stressed.

The trough 10 is provided at the sides with adjustable arms 44 which carry depending guides 44a engageable with the side edges of the fabric tube F as it moves along the trough. Similar adjustable guides (not shown) may be arranged at other parts of the trough to guide the fabric in its movement.

As disclosed in my copending application previously identified, the shrink-proofing process is completed by passing a high frequency alternating current through the de-stressed fabric F, as by transferring the hollow mandrel 40 to a dielectric heater and utilizing the mandrel as an electrode and also as a duct for blowing pre-heated air through the fabric coil during the dielectric heating. However, the de-stressed fabric withdrawn from the trough 10 may be passed continuously through the field of the high frequency current, so that the process is entirely continuous.

I claim:

1. Apparatus for relieving internal stresses in a length of textile fabric, which comprises a container for a liquid wetting agent, a conveyor for moving the fabric lengthwise through the liquid in a submerged path under substantially tensionless and compressionless conditions, a guide plate located in the container below the liquid surface but above said path, and means for introducing air into the container below said path to urge the fabric upward against the guide plate and thereby spread the fabric.

2. Apparatus for relieving internal stresses in a length of textile fabric, which comprises a container for a liquid wetting agent, a conveyor for moving the fabric lengthwise through the liquid in a submerged path under substantially tensionless and compressionless conditions, a guide plate located in the container below the liquid surface but above said path, the guide plate being generally horizontal and imperforate except for air vents adjacent the edge portions of said path, and means for introducing air into the container

below the plate and between said edge portions, whereby movement of the air through the liquid from said means to the vents acts to spread the fabric against the bottom of the guide plate.

3. Apparatus for relieving internal stresses in a length of textile fabric, which comprises a container for a liquid wetting agent, a conveyor for moving the fabric lengthwise through the liquid in a submerged path under substantially tensionless and compressionless conditions, means for introducing air into the container below said path, to urge the fabric upward in the liquid, and a guide plate immersed in the liquid above said means and path and operable to direct the air from said means laterally of the fabric path to spread the fabric against the bottom of the plate.

4. Apparatus for relieving internal stresses in a length of textile fabric, which comprises a container for a liquid wetting agent, a conveyor for moving the fabric lengthwise through the liquid in a submerged path under substantially tensionless and compressionless conditions, means for introducing air into the container below said path, to urge the fabric upward in the liquid, said means being located between the opposite edge portions of the fabric path, and a generally horizontal guide plate immersed in the liquid above said means and path and extending continuously from one edge portion of the path to its other edge portion, the bottom of the plate slanting downward from said edge portions toward said means, whereby the plate directs the air from said means laterally of the fabric path to spread the fabric against the bottom of the plate.

5. Apparatus for relieving internal stresses in a length of textile fabric, which comprises a container for a liquid wetting agent, a conveyor for moving the fabric lengthwise through the liquid in a submerged path under substantially tensionless and compressionless conditions, means for introducing air into the container below said path, to urge the fabric upward in the liquid, and a guide plate immersed in the liquid above said means and path and having a bottom surface slanting upwardly and outwardly from said means toward at least one edge portion of the fabric path, to direct the air from said means laterally of the fabric path and thereby spread the fabric against the bottom of the plate.

6. Apparatus for relieving internal stresses in a length of textile fabric, which comprises a container for a liquid wetting agent, a conveyor for moving the fabric lengthwise through the liquid in a submerged path under substantially tensionless and compressionless conditions, an air pipe in the container below said path and extending lengthwise of said path between its edge portions, the pipe having air outlet openings spaced along said path, and a guide plate immersed in the liquid above said path and pipe and having a bottom surface slanting upwardly and outwardly from the pipe toward at least one edge portion of the fabric path, to direct the air from the pipe openings laterally of the fabric path and thereby spread the fabric against the bottom of the plate.

7. Apparatus for relieving internal stresses in a length of textile fabric, which comprises a trough for a liquid wetting agent, a receptacle communicating with one end of the trough and adapted to receive the fabric, a conveyor for moving the fabric lengthwise from the receptacle through the liquid in the trough in a submerged

path, under substantially tensionless and compressionless conditions, to the other end of the trough, a spreader located intermediate the ends of the trough below the surface of the liquid adjacent said path and operable on the submerged fabric to spread the same under said surface, and a fabric untangling device operable on the fabric passing from the receptacle to the trough.

8. Apparatus for relieving internal stresses in a length of textile fabric, which comprises a trough for a liquid wetting agent, a receptacle communicating with one end of the trough and adapted to receive the fabric, a conveyor for moving the fabric lengthwise from the receptacle through the liquid in the trough in a submerged path, under substantially tensionless and compressionless conditions, to the other end of the trough, a spreader located intermediate the ends of the trough below the surface of the liquid adjacent said path and operable on the submerged fabric to spread the same under said surface, and an air duct in the receptacle and operable to deliver air to the underside of the fabric passing from the receptacle to the trough.

9. Apparatus according to claim 7, in which said untangling device is an oscillating member disposed in the receptacle.

10. Apparatus for relieving internal stresses in a length of textile fabric, which comprises a

trough for a liquid wetting agent, a receptacle communicating with one end of the trough and adapted to receive the fabric, a conveyor for moving the fabric lengthwise from the receptacle through the liquid in the trough in a submerged path, under substantially tensionless and compressionless conditions, to the other end of the trough, a spreader located intermediate the ends of the trough below the surface of the liquid adjacent said path and operable on the submerged fabric to spread the same under said surface, and an oscillatable air duct engageable with the underside of the fabric passing from the receptacle to the trough.
